UNITED STATES PATENT OFFICE.

PETER T. COFFIELD, OF NEW CARLISLE, OHIO, ASSIGNOR TO HIMSELF,
CHARLES H. NEFF, AND ALBERT L. WOOLEY, OF SAME PLACE.

WINDMILL.

SPECIFICATION forming part of Letters Patent No. 310,385, dated January 6, 1885.

Application filed March 22, 1884. (No model.)

To all whom it may concern:

Be it known that I, PETER T. COFFIELD, a citizen of the United States, residing at New Carlisle, in the county of Clark and State of Ohio, have invented new and useful Improvements in Windmills, of which the following is a specification.

This invention relates to improvements in that class of attachments for windmills or engines in which automatic devices are employed for locking and unlocking a geared windmill to the derrick. It is well known that when a windmill is geared for the purpose of running a shaft to which machinery is attached and resistance is applied to the shaft running vertically through the mill there is a tendency to walk away from the work, and also move out of the line of the wind, thereby losing power and placing the wind-wheel in such a position that the wind cannot drive it.

The object, therefore, of my invention is to provide means by which the wind-wheel is prevented from being thrown out of the wind's eye, but constantly kept to its work, and thus to impart a regular movement to the gearing for transmitting the motion to the machinery or other object to be driven, and to do this in a very simple and reliable manner, so that the mill will perform its work without sudden shocks, by which the machinery is easily disarranged, and also that the full power may be exerted, no matter how much the wind changes. This I accomplish in the manner and by the mechanism hereinafter described and claimed, reference being made to the accompanying drawings, illustrating my invention, in which—

Figure 1 represents a plan or top view of my improvement in position and properly geared for operating the machinery. Fig. 2 is a side elevation of the same. Fig. 3 is a side elevation taken at right angles to Fig. 2. Fig. 4 is an enlarged sectional view of the box for the push-bar or spindle, containing a spring to prevent shocks or sudden jars to the operating mechanism; Fig. 5, an end view of the same. Fig. 6 is a detail view of the clutch or brake lever. Fig. 7 is a detail sectional view of the brake-lever when forced against the bed or derrick plate by means of the spring presser-
50 foot, on an enlarged scale.

Like letters of reference indicate like parts in all the figures.

In the said drawings, A indicates the top or upper end of the mast or derrick, to which the circular bed-plate B is secured. The main vertical shaft C passes through this plate, and has a sleeve, c, upon which the vane-bar D freely revolves through the medium of an arm, a, secured to the vane-bar and journaled on the sleeve c.

To the upper end of the shaft C a bracketed plate, E, is secured by a set-screw or otherwise, and having at one side a bearing, e, for the driving-shaft e', which is journaled at its opposite end in an arm, e'', that is extended upward, and has attached to it a guy rod or brace, f, connected to the vane-bar, to assist in supporting it. A pinion, b, on the shaft e' meshes with a gear-wheel, d, secured to the shaft C, and imparts motion to the machinery, pumps, &c., when acted on by the wind-wheel.

At one side of the bracketed plate E is secured a bent or curved arm or lever, g, which bears against a push-bar, h, arranged in a box, h'. This box is provided with trunnions h'', and is journaled in the standards or brackets i, secured to the vane-bar, so that said box can freely oscillate. The push-bar h is reduced at one end, and has a coiled spring, h', around it, which bears against a shoulder 80 in said box h', the object of the spring being to prevent any sudden shock or jarring to the gearing and machinery when the arm g comes in contact with the push-bar h. To the opposite end of this push-bar is pivoted the 85 lever F, having at its upper end a slot fitting over the reduced end of said push-bar, and allowing the lever to oscillate freely on it as it moves. The lever F is provided with an open slot, f', having sharp edges, which form clamping or gripping jaws when the lever is tilted, one side of said jaws engaging with the upper end and the other side with the lower surface of the circular bed-plate B. The lower end of the lever F is extended, and when the vane-bar moves in that direction it comes in contact with an arm or bent lever, k, secured to the lower side of the vane-bar, and releases the lever F from its gripping action on the bed-plate.

At the rear side of the lever F is secured a 100

spring presser-foot, *l*, which bears on the upper surface of the bed-plate *B*, and always holds the lever in contact with said plate and in position, and prevents the possibility of said lever slipping, thus forming an automatic clutch or brake lever. The vane will locate itself in line with the wind, and the bracketed plate is brought to a stop by coming in contact with the spring push-bar, which, pressing against the spring within the pivoted box, obviates any shock, and, passing through said box, it fastens the clutch on the surfaces of the bed-plate.

Having thus described my invention, what I claim is—

1. In a windmill, a spring push-bar provided with a pivotal clutch-lever for engaging with a circular base-plate, and acted on by an arm or lever attached to the vane-bar of the mill, substantially as described.
2. In a windmill, a pivoted clutch-lever provided with spring presser-foot engaging with both sides of a circular bed-plate, and operated by a spring push-bar and an arm attached to the vane-bar, substantially as described.
3. In a windmill, the combination, with a circular bed-plate, of a spring push-bar mounted in a pivoted box secured to the vane-bar, and attached at one end to a clutch-lever, and acted against at the opposite end by an arm connected to the bracketed plate *E*, substantially as described.
4. In a windmill, a clutch-lever having jaws to engage with the upper and lower surface of a circular bed-plate attached to the upper end of the derrick, and operated by a spring push-bar, against which an arm on the vane-bar bears, and a spring presser-foot, substantially as described.
5. The combination, with a circular bed-

plate, of a spring push-bar mounted in a pivoted box, and connected to a clutch-lever at one end, and acted against by an arm connected to the wheel-frame, with an arm secured to the lower side of the vane-bar, for the purpose of unlocking the clutch-lever, substantially as described.

6. The combination, with a circular bed-plate, of a spring push-bar mounted in a pivoted box journaled in standards on the vane-bar, and connected at one end to a pivoted clutch-lever provided with a spring presser-foot, and having clamping-jaws, with an arm secured to the lower side of the vane-bar, and an arm connected to the supporting-frame, all arranged for operation substantially as described.

7. The combination, with a circular bed-plate, of a spring push-bar mounted in a box having trunnions journaled in standards on the vane-bar, and connected at one end to a pivoted clutch-lever, with an arm attached to a bracketed plate secured to the bearing of the vertical shaft, and carrying the gearing and wind-wheel shaft, substantially as described.

8. The combination, with a circular bed-plate, of a spring push-bar, a pivoted clutch-lever secured thereto, and carrying a spring presser-foot, with an arm attached to a bracketed plate secured to the bearing of the vertical shaft, and carrying the gearing and the wind-wheel shaft, all arranged substantially as described.

In testimony whereof I have hereunto set my hand in the presence of two subscribing witnesses.

PETER T. COFFIELD.
